UNITED STATES PATENT OFFICE.

FRANK D. WARD, OF NEW YORK, N. Y.

DOOR-OPERATING ENGINE.

1,260,838.

Specification of Letters Patent. Patented Mar. 26, 1918.

Application filed February 27, 1917. Serial No. 151,291.

To all whom it may concern:

Be it known that I, FRANK D. WARD, a citizen of the United States, and a resident of the borough of Manhattan, city and State of New York, have invented certain new and useful Improvements in Door-Operating Engines, of which the following is a description in such full, clear, and exact terms as will enable any person skilled in the art 10 to which it pertains to make and use the same.

My invention relates to a device intended especially, though not necessarily, for operating the doors of street railway cars. The 15 device, however, is useful in various other connections as will be apparent to skilled mechanics.

The object of the invention is to provide an effective and practicable compressed air 20 or other fluid motor under electrical control and provided with motion transmitting devices adapting it especially to be used for operating the doors and "interlock" of so-called "pay-as-you-enter" street railway cars 25 or other analogous apparatus.

To this end the invention consists in certain novel features of construction and combinations of parts which will be fully set forth hereinafter and particularly pointed 30 out in the claims.

Reference is had to the accompanying drawings which represent as an example, the preferred embodiment of my invention.

In these drawings—

35 Figure 1 is a longitudinal section of the device.

Fig. 2 is a similar section except that the valve devices are shown in elevation and the piston of the motor or engine is illustrated 40 in the position opposite to that shown in Fig. 1, and

Fig. 3 is a cross section on the line 3—3 of Fig. 2.

5 indicates the cylinder of the engine or 45 motor and 6 and 7 indicate the heads thereof. The cylinder 5 is preferably formed of wrought or drawn seamless metal and the heads 6 and 7 are cast in suitable form.

Operating in the cylinder 5 are pistons 8 50 and 9 of the usual or any desired construction rigidly connected by a rod 10. The piston 8 has a lug 11 thereon to which a bent or substantially U-shaped arm or elbow 12 is pivoted at one end. The other end 55 portion of this arm 12 plays freely through a longitudinally disposed slot 14 in the cyl-

inder 5 and is pivoted to a thrust rod 15 located outside of the cylinder, the pivot operating in parallel guides 16 fastened to and extending along the cylinder as shown 60 in the drawings.

The motive fluid acts on the outer faces of the pistons 8 and 9, the space between the pistons being exposed to atmospheric pressure through the slot 14. This allows the 65 elbow arm 12 to slide freely with the pistons and owing to the form of the arm and the arrangement of the guides 16 the arm has a certain swinging motion on its pivot simultaneously with its sliding motion and thereby the arm is caused to impart to the rod 15 70 a regular back and forth motion corresponding to the motion of the pistons.

The cylinder head 7 has a feed port 22 formed therein for the compressed air or 75 other motive fluid and the cylinder head 6 has a similar port to which a pipe or other connection 23 leads. The port 22 and pipe 23 communicate with the supply ports in a valve housing 30 which is fastened suitably 80 to a part of the cylinder head 7. Intermediate these supply ports is the usual exhaust port 33. Within the housing 30 is a slide valve 21 which alternately opens the pressure supply passages or ports 22 and 23 to the 85 source of pressure which enters the housing 30 through a supply pipe 32 (see dotted lines in Fig. 1). When one of the supply ports is opened to the pressure the other port is connected with the exhaust 33 according to 90 the usual slide valve practice and by the regular operation of the valve 21 pressure is alternately admitted to and exhausted 95 from the ends of the cylinder 5 causing reciprocation of the pistons 8 and 9 therein.

Air tight housings 17 and 18 are joined to the valve housing 30 at opposite sides thereof and contain solenoid magnets with which the armatures 19 and 20 respectively operate. These armatures are connected by brass 100 or other non-magnetic rod 31 which engages the slide valve 21 so that reciprocation of the solenoid armatures 19 and 20 causes the slide valve 21 to take its characteristic back and forth motion and thereby control 105 the pressure to the cylinder 5.

In order thus to operate the slide valve it is necessary, according to the wellknown practice, to alternately energize the solenoid magnets. This may be done by a switch or 110 control device of any desired kind (not shown).

24 indicates an electric switch which controls an electric circuit, said switch preferably attached to the cylinder head 6 and joined to a wooden or other non-conducting rod 29. Said rod has a slot 28 in its end opposite the switch 24 which receives a pin connection on the end of a rocking lever 26. The lever 26 is fulcrumed at 27 and its inner end engages a leaf spring 30 by which spring the lever is releasably held in either one of its extreme positions. The outer end of the lever 26 is forked and adapted to be engaged by a pin 25 on the thrust rod 15 whereby the lever is rocked back and forth 15 making or breaking the circuit of the switch 24 as the rod 15 reciprocates.

It should be noted that the metal casings 17 and 18 of the solenoid magnets are hermetically joined to the valve housing 30 and 20 that there is no communication between the interior of these parts and the atmosphere. Hence the armatures 19 and 20 have a sort of dash pot action in the solenoids which cushions the stroke of the valve 21 and armatures 19 and 20 and renders the operation of the valve regular and noiseless.

In the operation of the device alternate energization of the solenoids will result in reciprocation of the valve 21 and the alternate admission of pressure to and exhaust of pressure from the ends of the cylinder 5. This gives the pistons 8 and 9 and their connected parts 12 and 15 corresponding reciprocation and by the coaction of the parts 35 25, 26 and 29 the switch 24 is simultaneously operated to make and break the circuit to which it relates. The arm 15 may be connected to operate any desired device and the switch 24 may be connected to control an 40 electric circuit having relation to the device operated by the arm 15.

Assuming, however, that the invention is applied to the operation of the usual sliding or swinging doors of the so-called "pay-as-you-enter" street railways cars (to which indeed it is especially adapted); then the circuit of the solenoids 17 and 18 is placed under the control of the conductor of the car (by the usual or any known form of 45 switch device not shown); the arm 15 is mechanically articulated to the car doors to give them their necessary sliding or other motion, to open or close; and the circuit of the switch 24 is made to control the usual 50 interlocking device of modern electric street railway cars by which device the motorman is prevented from starting the car until the doors are shut by the conductor. This "interlocking" device is well-known in electric 55 street railway practice; it forms no part of my invention and is not here shown.

When the invention is so connected and arranged, the car conductor controls the circuits of the solenoids to actuate the valve 21 60 and through it to bring about reciprocation

of the parts 8, 9, 10, 12 and 15 to open and close the doors of the car, and the switch 24 controls the "interlock" circuit so that the car cannot be started until the doors are closed, all of which connections will be understood by persons skilled in the art. 70

What I claim is:

1. A motor having a cylinder with an intermediate opening, two rigidly connected pistons, an elbow arm one end of which is 75 articulated to the pistons and the other end of which strokes through the opening in the cylinder and a device operated by said elbow arm.

2. A motor having a cylinder, connected 80 pistons operating in the cylinder, the cylinder having an opening in its side, and a return bent or U-shaped arm, one end thereof lying longitudinally in the cylinder and articulated to the pistons and the other end 85 thereof adapted to stroke in and out of the cylinder through said opening in its side.

3. A motor having a cylinder with an intermediate opening in its side, connected 90 pistons in the cylinder on opposite sides of the opening and a return bent or U-shaped arm one part thereof extending longitudinally in the cylinder between the pistons and articulated thereto and the other part thereof of adapted to stroke in and out of the cylinder through said opening therein. 95

4. A motor having a cylinder, connected pistons operating in the cylinder, the cylinder having an opening in its side, and a return bent or U-shaped arm, one end thereof 100 lying longitudinally in the cylinder and articulated to the pistons and the other end thereof adapted to stroke in and out of the cylinder through said opening in its side, and means outside of the cylinder for laterally guiding said arm. 105

5. A motor having a cylinder with an intermediate opening in its side, connected pistons in the cylinder on opposite sides of the opening and a return bent or U-shaped 110 arm one part thereof extending longitudinally in the cylinder between the pistons and articulated thereto and the other part thereof of adapted to stroke in and out of the cylinder through said opening therein, and means outside of the cylinder for laterally guiding the said arm. 115

6. A motor having a cylinder, connected pistons operating therein, a return bent or U-shaped arm, one end of which is articulated to the pistons and moves with them longitudinally in the cylinder, the other end of said arm adapted to stroke in and out of the cylinder through an opening therein, in direction longitudinal of the cylinder for 120 the purpose specified. 125

7. A motor having a cylinder, connected pistons operating therein, a return bent or U-shaped arm, one end of which is articulated to the pistons and moves with them 130

longitudinally in the cylinder, the other end of said arm adapted to stroke in and out of the cylinder through an opening therein, in direction longitudinal of the cylinder, a 5 thrust rod connected to the second part of said arm and an electric switching device operated from said thrust arm.

8. A motor having a cylinder with an intermediate opening, pistons operating in the 10 cylinder and at opposite ends of the opening, means connecting the pistons together, a return bent or U-shaped arm, one part of which moves longitudinally in the cylinder and is located between the pistons and articulated thereto and the other arm of which 15 strokes in and out of the cylinder through said opening in the side thereof.

9. A motor comprising a cylinder with an intermediate opening, connected pistons 20 operating in the cylinder at opposite ends of the opening, a return bent or U-shaped arm articulated to the pistons at its inner part, said inner part moving longitudinally in the cylinder and between the pistons and the other part of the arm stroking in and out 25 of the cylinder through the opening therein,

a thrust rod pivoted to the second named part of the arm and means outside of the cylinder for laterally guiding the arm and thrust rod.

10. A motor comprising a cylinder with an intermediate opening, connected pistons operating in the cylinder at opposite ends of the opening, a return bent or U-shaped arm articulated to the pistons at its inner 30 part, said inner part moving longitudinally in the cylinder and between the pistons and the other part of the arm stroking in and out of the cylinder through the opening 35 therein, a thrust rod pivoted to the second named part of the arm and means outside of the cylinder for laterally guiding the arm and thrust rod and an electric switch operated by said thrust rod.

In testimony whereof I have hereunto 40 signed my name in the presence of two witnesses.

FRANK D. WARD.
